AFTERBURNERS

Paul A. Pitt, San Diego, Calif., assignor to Solar Aircraft Company, San Diego, Calif., a corporation of California

Application May 18, 1950, Serial No. 162,723

7 Claims. (Cl. 60—39.72)

This invention relates to improvements in combustion apparatus for burning fuel in a high velocity blast of air or gas, and has particular reference to a burner for continuously burning at high altitude a mixture of combustible and combustion supporting elements in a high velocity stream to develop reactive forces in, and to increase the reactive forces of, the stream.

The subject invention is an improved burner of the type disclosed in co-pending application Serial No. 140,633, filed January 26, 1950, by Robert E. Day, now Patent No. 2,701,444, issued February 8, 1955. These burners are presently used in jet engine assemblies for jet powered aircraft, and the improvement in the embodied invention resides in substantially increased burner, and therefore engine, performance at very high altitudes.

As explained in Patent No. 2,701,444, hereinbefore cited, the fuel manifold in this type of burner is equipped with gutters or flame holders which anchor pilot flames thereto. The pilot flames in turn mix with and ignite the fuel-exhaust gas mixture passing between the gutters to instigate the main combustion which increases the reactive forces of the mixture. The flame front or upstream boundary of this main combustion is normally located well forward in the jet engine tailpipe, not far downstream of the fuel manifold and gutters. However, I have discovered that as the altitude is increased the point of maximum heat release gradually moves further downstream from the gutters towards the after end of the tailpipe until considerable difficulty is experienced in obtaining effective burning at very high altitudes.

This difficulty is characterized by only part of the heat being released from the fuel before it leaves the tailpipe as the plane gains altitude. The further the intergutter flame front recedes the less complete is the combustion before ejection.

At very high altitude combustion probably ceases or the burning occurs outside of the jet engine nozzle. It will be understood that fuel burned after passing through the jet nozzle contributes nothing toward driving the aircraft forward and represents only lost energy and an ultimate ineffectiveness of the jet engine afterburner. Blowout occurs because primary combustion must make up for the lack of secondary combustion hence the fuel control continues to meter a greater quantity of fuel to the gutters which reaches a point where mixture is overrich and can no longer burn.

To overcome these problems encountered in the burners of the prior art the invention embodied herein provides a high altitude burner which employs a secondary flame anchoring gutter or flame holder downstream of the primary gutters as a flame anchor or stabilizer for the main combustion. This novel construction enables a materially improved afterburner performance at high altitude and at the same time in no way impairs the excellent performance of this type of burner at lower altitudes. Also, due to the location and construction of this secondary flame anchoring gutter, to be fully described hereinafter, very little is added to the total resistance to

2

flow through the burner, under non-afterburning conditions and at the same time combustion is completed in a shorter distance, so that the tailpipe length downstream of the burner may be desirably shortened. In addition, an important feature of this invention is that it is possible to burn nearly the maximum amount of fuel with respect to the mass flow of air supplied, particularly at peak altitudes, thereby gaining the utmost in thrust. This very considerable increase in thrust represents a great improvement in the military effectiveness of an aircraft as this additional power may well mean the difference between winning and losing a fight, getting away or overtaking in pursuit.

With these and other considerations in view it is a prime object of this invention to provide a burner for jet engine afterburner assemblies which will enable top engine performance at very high altitudes.

It is a further important object of this invention to provide a high altitude burner which enables top engine performance at low altitudes as well as high altitudes.

Another important object is to provide a high altitude burner which presents a minimum of resistance to flow of exhaust gases through the burner and only a negligible increase in back pressures.

Another object is to provide a high altitude burner which anchors the main combustion of the fuel-exhaust gas mixture within the tailpipe of the jet engine.

A still further object is to provide a simply constructed high altitude burner which is both dependable and highly efficient over a very great range of altitude.

Another object is to provide a burner in which combustion is more rapidly completed, permitting use of shorter stack sections.

Other objects and advantages will be apparent from the following description in conjunction with the accompanying drawings and from the appended claims.

The accompanying drawings, in which like reference numerals are used to designate similar parts throughout, illustrate the preferred embodiment for the purpose of disclosing the invention. The drawings, however, are not to be taken in a limiting or restrictive sense, since it will be apparent to those skilled in the art that various changes in the illustrated construction may be resorted to without in any way exceeding the scope of the invention.

In the drawings:

Figure 1 is a side elevation of a jet engine afterburner assembly;

Figure 2 is an enlarged front elevation of the burner embodying the invention, taken along line 2—2 of Figure 1;

Figure 3 is a section of the burner of Figure 2, taken along line 3—3 of Figure 2, showing the primary and secondary pilot flame patterns;

Figure 4 is a section of the burner of Figure 2, taken along line 4—4 of Figure 2; and

Figure 5 is a graph illustrating the relationship between heat generated during combustion vs. distance downstream from primary gutter at various altitudes.

Referring to Figure 1, reference number 20 generally indicates a jet engine after burner assembly such as that described in Patent No. 2,701,444, comprising a diffuser 24, a burner housing or shell 25 and a tailpipe 26. The diffuser 24 and tailpipe 26 are secured to cylindrical housing 25 through a pair of peripheral welded flanges 27 and 28 by means of bolts 31 and complementary flanges 32 and 33 welded to sections 24 and 26, respectively.

Since the basic burner assembly mounted within the burner housing 25 is described in detail as to construction and operation in Patent No. 2,701,444 the burner will be only generally described herein. Referring to

Figure 2, it will be seen that the fuel distribution grid, indicated generally at 34, and a grid formed by a compound carburetion and combustion gutter, indicated generally at 35, are disposed within the burner housing 25. Both grids are sufficiently smaller in diameter than housing 25 to provide an annular area 30 for the passage of a layer of protective gases between the burner structure and the housing which prevents serious overheating of the housing when large volumes of fuel are burned. The fuel distribution grid 34 comprises an intercommunicating network of tubes or pipes, some of which are arranged concentrically within the housing 25 and others radially. In the illustrated embodiment the pipes forming the fuel distribution grid are coplanar. The grid 34 includes a diametrically extending generally vertical pipe 36 and a generally horizontal pipe 37 which extend to and communicate with a circular pipe 38. Two other circular pipes 41 and 42, spaced inwardly and concentric with the pipe 38, connect the pipes 36 and 37 at other points. A series of equiangularly spaced radial pipes 43 bridge the space between the outer circular pipe 38 and the adjacent circular pipe 41, except that there are no such radial pipes in the places already occupied by the vertical and horizontal pipes 36 and 37, since the pipes 36 and 37 already connect the circular pipes 38 and 41 at those locations. All of the pipes forming the fuel distribution grid 34 have openings 44 facing generally upstream into the exhaust or other gases, i. e. towards the diffuser 24 of the afterburner assembly.

The fuel distribution grid 34 is mounted within the cylindrical housing or shell 25 in the following manner. At points coaxial with the vertical and horizontal pipes 36 and 37, four tubular axial extensions 45 are welded to the outer circular pipes 38. Three of the extensions 45 have a slip fit into a streamlined tubular socket 46 having an integral peripheral flange 47 that is welded to shell 25. Thus, while the fuel distribution grid is rigidly located within the housing 25, it is free to expand and contract with temperature changes without imposing stresses on the housing that would tend to deform it.

Fuel is fed to the grid 34 at or near the bottom thereof by means of an inlet pipe 53 which passes through a stuffing box 54, Figures 2 and 3, into the interior of the shell 25 and is connected to the extension 45 at the lower end of the vertical pipe 36. The inlet pipe 53 provides the fourth radial support for the fuel distribution grid 34, and the stuffing box 54 provides for any axial movement of the inlet pipe 53 caused by expansion or contraction of the grid 34. The fuel thus enters the fuel distribution grid 34 at the bottom thereof and rises within the intercommunicating network of pipes, filling it to the top and causing any gas within the pipes to be completely displaced.

Carried by the fuel distribution grid 34 and disposed downstream thereof, or within the portion of the housing 25 adjacent the tailpipe 26, is the compound carburetion and combustion gutter network or grid 35. This grid 35 is arranged transversely of the housing 25 as is the fuel distribution grid 34, and in the illustrated embodiment is planar and parallel to the fuel distribution grid. The grid 35 is made up of several portions, substantially identical in cross-section as appears in Figures 3 and 4, and is positioned directly downstream of several elements of the pipe forming the fuel distribution grid 34. It comprises an outer compound gutter ring generally indicated at 55, and an inner compound gutter ring generally indicated at 56, downstream of the circular fuel distribution pipes 38 and 41, respectively. As shown in cross-section in Figure 3, each compound gutter ring comprises a pair of concentric, spaced walls 57 and 58 rigidly connected by a continuous transverse trough shaped common member or connecting wall 61 which divides the compound gutter into a downstream facing combustion gutter or trough 62 and an upstream facing carburetion gutter or trough 63. The outer and inner compound gutter

rings 55 and 56 are connected by four equiangularly spaced radial compound gutters 66 of similar cross-section, that lie directly downstream of the vertical and horizontal fuel distribution pipes 36 and 37. The compound radial gutters 66 are provided with connecting members 61a dividing the gutters into downstream facing combustion gutters 62a and upstream facing carburetion gutters 63a.

The compound gutter grid 35 is mounted upon the fuel distribution grid in such a manner as to allow relative differential expansion and contraction therebetween. This is accomplished as by means of pairs of yokes 67, Figures 2 and 3, and 4, that have a sliding fit on pipes 36 and 37 of the fuel distribution grid. The yokes extend towards and embrace the outer walls of the radial compound gutters 66, to which they are rigidly secured through pins 68.

Those portions of the vertical and horizontal fuel distribution pipes 36 and 37 upstream of the radial compound gutters 66 having downstream directed fuel discharge openings 69, Figures 3 and 4, that discharge pilot fuel downstream into the carburetion gutter section 63a of the compound gutters 66. The circular pipes 38 and 41 also have downstream directed fuel discharge openings 71, Figure 3, that discharge pilot fuel into the circular carburetion gutters 63 of the compound gutter rings 55 and 56, respectively. This fuel may be target atomized when it strikes common members 61 and 61a in the compound gutter system that divides the carburetion gutter from the combustion gutter. These members 61 and 61a have openings 72 and 72a respectively therethrough to permit the passage and impacting of the atomized fuel against walls 57 and 58 and 66 and into the combustion gutters 62 and 62a where it burns to form an igniting and combustion sustaining flame. Instead of projecting the pilot fuel downstream, openings 69 and 71 may also be arranged to discharge the pilot fuel upstream in addition to the fuel discharge through openings 44 so that it is carried by the high velocity gases into the carburetion gutters, giving adequate pre-combustion mixing time and improved high altitude operation.

Since the exhaust gases are traveling through the housing 25 at speeds of over three hundred miles per hour, a portion thereof enters the carburetion gutters 63 and 63a wherein it circulates turbulently and mixes thoroughly with the atomized fuel within the gutter, thereby also preheating the fuel, and the mixture passes through the openings 72 into the combustion gutters 62 and 62a striking against the hot walls 57 and 58 and 66 by reason of the inclination of the connecting walls 61 and 61a and the holes 72 and 72a.

A pair of spark plugs 73 and 74 are mounted in reinforced sections of the housing 25 adjacent to the bottom thereof, one on each side of fuel pipe 53, with their electrodes extending into the combustion gutter 62 of the outer ring 55, as shown in Figure 2. These spark plugs are one example of means which can be used to ignite the mixture in the compound gutter, which once ignited provides a pilot flame that courses rapidly through the outer, inner and radial combustion gutters 62 to establish a pilot flame grid which continues to burn until the fuel supply to the fuel distribution grid 34 is cut off.

This pilot flame pattern which is established and anchored at its forward end by the combustion gutters 62 and 62a is illustrated diagrammatically at 80 in Figure 3, and will be referred to hereinafter as the primary pilot flame. As explained in detail in Patent No. 2,701,444 this pilot flame serves to initiate the main combustion in the fuel-exhaust gas mixture passing between the compound gutters. However, as pointed out hereinbefore, these primary flames lengthen more and more and the point of maximum heat release of the main combustion retreats farther and farther downstream at increasingly high altitudes with ultimate blow-out.

As has also been explained hereinbefore, at very high altitudes, the main combustion flame front will have retreated so far downstream that at least a portion of the fuel-gas mixture will pass out of the jet engine nozzle unburned, representing lost energy as far as concerns the propelling of the aircraft. To eliminate this high altitude problem, this invention, in the embodiment disclosed, provides a secondary combustion gutter ring 82, Figures 2, 3, and 4, located downstream of, and spaced radially between, the compound gutter rings 55 and 56. The secondary combustion gutter ring 82 has a V-shaped cross-section, although it is within the scope of the invention that the gutter ring be of any suitable cross-section. The gutter ring is mounted with its open side facing downstream, as is best illustrated in Figure 3, and is carried by the compound gutter grid 35 by means of four pairs of channel members 84 welded or otherwise suitably fastened at their forward or upstream ends to the four radial compound gutters 66, Figures 2, 3, and 4. The channel members 84 are secured at their other ends to four pairs of brackets 85 in alignment therewith which are welded to the back of the gutter ring 82. The brackets 85 are cut away as shown in Figure 3 to fit closely over the back of the V-shaped gutter 82 to enable them to be securely welded thereto. Brackets 85 and channel members 84 are fastened together by some suitable means as bolts 86 which rigidly locate the gutter 82 while at the same time allowing it to be easily removed if desired, and also allowing for relative differential expansion and contraction between the gutter 82 and the compound gutter grid 35.

Referring now to Figure 3, it will be seen that the secondary gutter ring 82 has anchored thereto a secondary pilot flame or stabilizing flame which at very high altitudes prevents the main combustion flame front from retreating too far downstream in the tailpipe, and keeps it instead well upstream in the immediate area of the compound gutter grid 35. This secondary pilot flame indicated at 87 in Figure 3 is initiated in the following manner. The main stream of fuel-exhaust gas mixture which passes between the primary compound gutters has a tendency to eddy about and recirculate in the secondary gutter 82 as indicated by the arrows 88. This eddying and recirculation gives the mixture a greater chance to mature towards its ignition point, and this maturing process is also aided by the direct radiant heat of the primary pilot flame 80 and by the fact that the primary flame pattern has caused the secondary gutter 82 to be substantially heated. The combination of these factors, i. e. the opportunity for rapid maturing of the fuel-gas mixture plus the proximity of the mixture to high heat, aids the bridging of flame into this area, forming the secondary flame 87. In actual practice the whole process of ignition to form a secondary plane takes place at high altitudes with extreme rapidity, probably in $\frac{1}{100}$ of a second or less. Furthermore, once the flame is initiated in the gutter, it will remain a stable pilot flame as long as the after-burner is in operation since the eddying and recirculation of the fuel-gas mixture which would tend to decrease the stability of the flame becomes less due to localized burning and expansion.

Once the secondary pilot flame is formed, the main combustion flame front no longer tends to retreat downstream but will in effect be stabilized or anchored well upstream approximately in the area indicated by the dash lines 89. This occurs because the secondary pilot flame 87 causes the fuel-exhaust gas mixture passing between the primary gutters to mature rapidly well upstream and be ignited by the adjacent primary pilot flame 80, or by the secondary pilot flame itself. Thus, the secondary flame in a sense plugs the gap in the primary flame pattern, which gaps assume a large importance at high altitudes. It should be pointed out here that

at altitudes of lower than 40,000 feet the process just described in connection with the ignition of the secondary pilot flame 87, probably does not occur to a substantial degree since at the lower altitudes higher absolute pressures within the afterburner cause the fuel-gas mixture to mature and burn more rapidly so that the main combustion flame front is retained in the immediate area or upstream of the secondary gutter 82.

It is of considerable importance that the addition of the secondary gutter 82 to the burner adds very little to the total resistance to flow of gases through the burner, under non-afterburning conditions, due to the fact that it is located downstream of the main compound gutter grid 35, and is of less projected area than that at the primary gutters. It might appear that the secondary gutter could also be placed in the same plane as the primary gutters 62 and 62a to stabilize the main combustion at high altitudes, but doing this would increase the per cent of coplanar solid matter in the afterburner and therefore materially increase the resistance to flow of the exhaust gases through the afterburner. A further important advantage of the downstream location of the secondary gutter 82 is that the added secondary pilot flame 87 causes far less back pressure in this location than if it were in the same plane as the primary pilot flame, also there is greater heat available to mature the mixture.

The graph of Figure 5 has been included in the drawings to give a visual presentation of approximately what takes place during combustion in the afterburner tailpipe at various altitudes. The curves of this graph are plotted from data obtained from experimental operation in a test cell with simulated altitudes. The abscissas of the curves are in terms of distance downstream from primary gutter, while the ordinates are in terms of B. t. u. produced during combustion in the tailpipe. The solid line curves indicate the B. t. u. yielded by the primary and secondary combustion gutters together and are labelled "Total." The curves in phantom lines indicate B. t. u. produced by the primary gutter alone, and the curves in dash lines indicate B. t. u. that would be produced by the secondary gutter alone. It will be understood from the foregoing disclosure that combustion does not generally occur in the secondary gutter alone; for this reason coordinates for the secondary gutter curves were necessarily obtained by subtracting the values of the ordinates for the primary gutter alone from the values of ordinates for the primary and secondary gutters together. The curves illustrate the B. t. u. produced by the primary gutter alone, the secondary gutter alone and the total of primary and secondary gutters at sea level (S. L.), and at simulated 40,000 feet; and the total of primary and secondary B. t. u. at simulated 30-35,000 feet.

It will be observed that the total B. t. u. produced by the primary and secondary gutters together is greater in every case than the B. t. u. produced by the primary alone. This, of course, is an added advantage of the high altitude secondary burner. However, the most important point to be brought out by this graph is illustrated by the peak points 90 and 92 of the primary gutter curve at 40,000 feet and the primary and secondary total curve at 40,000 feet, respectively. These peak points represent the point of maximum combustion efficiency or maximum B. t. u. yield. It will be noted that peak point 90 of the primary curve is slightly to the left or upstream of the peak 92 of the total curve at 40,000 feet. However, as explained hereinbefore, this point recedes down the tailpipe at increasing altitudes above 40,000 feet. Thus if it were practical to include a series of graphs or many additional primary curves on the illustrated graph, the peak point would be seen to drift gradually to the right as the altitude increased. In each case the total effective B. t. u. made available by the burner without the additional secondary gutter is indicated by the

area under the primary curve and the additional thrust made available by the secondary gutter is represented in area under the secondary curves. Thus it will be seen that as altitude increases and the maximum combustion rate of the primary recedes downstream, the secondary plays a larger and larger part in release of the available B. t. u. within the tailpipe where it will add to the thrust of the plane. The vertical line 94 intersects the principal abscissa at a point equal to the length of the afterburner tailpipe. Area under the curves to the right of line 94 represents lost energy while area under the curves to the left of line 94 represents energy contributing to the propulsive thrust desired.

One further point which should be noted in connection with this graph is that as the altitude increases from sea level to 40,000 feet and above, the total B. t. u. produced by the primary and secondary gutters gradually decreases. This is a normal characteristic of a jet engine-afterburner combination and is due to the fact that as altitude is increased less mass of air is pumped through the system because of reduced air density. This does not mean, however, that the speed of the aircraft is necessarily reduced, since the lowering of B. t. u. output is in greater or less degree compensated for by the general decrease in resistance offered to the aircraft as it moves through the air.

Thus it will be understood that the invention embodied herein provides an efficient and dependable means of obtaining top afterburning performance at very high altitudes by stabilizing or anchoring the main combustion flame front well upstream in the afterburner tailpipe, thus eliminating any possible loss of thrust augmentation due to the fuel-gas mixture passing unburned through the tailpipe. At the same time this increased afterburner performance is obtained with but a negligible increase in back pressures and resistance to the flow of gases during nonafterburning, and as the combustion is completed more rapidly, the tailpipe may be shortened for a given fuel consumption rate, or the amount of fuel burned may be increased, thus increasing the capacity of a given prior stack length.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by the United States Letters Patent is:

1. In a combustion apparatus for increasing the mass and velocity of a confined stream of gases moving at high velocity; a duct having an inlet and outlet for said gases; a first grid of fuel distribution pipes adjacent the inlet of said duct for discharging fuel into said duct; a second grid between said first grid and the outlet of said duct comprising a carburetion gutter facing said first grid to receive fuel therefrom and a combustion gutter colinear with said carburetion gutter facing the outlet of said duct; said carburetion gutter and combustion gutter having common concentric side walls separated by a perforated cross-wall forming a communicating passage way between said gutters to allow fuel to pass from said carburetion gutter to said combustion gutter; and an additional combustion gutter facing downstream in said duct between said second grid and said outlet.

2. A combustion apparatus comprising a duct having an inlet and an outlet for admitting and discharging gases at high velocity; a first grid of fuel distribution pipes; a second grid having a pair of interconnected colinear carburetion and combustion gutters; and an intermediate interconnected combustion gutter secured to said second grid downstream thereof.

3. A combustion apparatus comprising a duct having an inlet and an outlet for admitting and discharging gases at high velocity; a first grid of fuel distribution pipes; a second grid having inner and outer concentric rings comprised of colinear carburetion and combustion gutters, said inner and outer concentric rings joined together by radial members comprised of colinear carburetion and combustion gutters; and an additional combustion gutter, secured to said radial members of said second grid downstream thereof and radially spaced between said pair of concentric rings of said second grid.

4. In a combustion apparatus for increasing the mass and velocity of a confined stream of gases moving at high velocity; a duct having an inlet and outlet for said gases, said duct including a mixing zone adjacent said inlet and a combustion zone downstream of said mixing zone and adjacent to said outlet; a distributor for adding and substantially evenly distributing fuel to the gases passing through said duct, comprising a grid of spaced fuel supply pipes arranged in said mixing zone transversely of said duct, certain of the pipes forming said grid having outlets discharging fuel downstream towards said combustion zone and others of said pipes having outlets discharging fuel upstream and away from said combustion zone; a second grid in said combustion zone comprising a series of carburetion gutters disposed transversely therein with their open ends facing those pipes in said fuel distributor having downstream facing openings, said second grid including a series of combustion gutters colinear with said carburetion gutters but having their open ends facing downstream, said carburetion gutters having communicating means with said combustion gutters to permit fuel from said carburetion gutters to enter said combustion gutters; and a third combustion gutter grid facing downstream in said combustion zone supported in spaced relation downstream of said second grid.

5. In a combustion apparatus for increasing the mass and velocity of a confined stream of gases moving at high velocity therethrough; a duct having a mixing zone and a combustion zone for said gases; a first grid in said mixing zone for distributing fuel to the gases passing therethrough; a second grid downstream of said first grid comprising a carburetion gutter to carburet fuel from said first grid and a combustion gutter having igniting means therein; and a third grid downstream of said second grid comprising a combustion gutter only; whereby mixed fuel and gases supplied to said combustion gutter from said carburetion gutter become ignited producing a primary pilot flame, and mixed fuel and gases eddying about the combustion gutter of said third grid become ignited producing a secondary pilot flame, said pilot flames in turn igniting the remaining mixed gases and fuel passing through said grids to cause main combustion of said mixture thereby forming a combustion pattern of main combustion in zones intermediate pilot flame zones in the combustion zone of said duct.

6. In a combustion apparatus comprising a duct having an inlet and outlet for admitting and discharging gases moving at high velocity, said duct including a mixing zone adjacent said inlet and a combustion zone downstream of said mixing zone and adjacent said outlet; a first grid in said mixing zone for distributing fuel to the gases passing therethrough; and a second grid for igniting and maintaining combustion of the mixed gases and fuel, comprising carburetion gutters facing upstream towards the inlet side of said duct, and combustion gutters facing downstream towards the outlet side of said duct and having igniting means therein; and a third grid downstream of said second grid comprising a combustion gutter only; whereby mixed gases and fuel entering said second grid are ignited to produce a plurality of interconnected primary pilot flames extending downstream of said second grid, and mixed fuel and gases entering said combustion gutter of said third grid are ignited to produce a secondary pilot flame extending downstream of said third grid,

said primary pilot flames serving to continuously ignite the remaining mixed gases and fuel passing through said grids to cause main combustion of the mixture, and said secondary pilot flame serving to anchor the main combustion flame front in the approximate area of the third grid at 5 high altitudes.

7. A combustion apparatus comprising a duct having an inlet and an outlet for admitting and discharging gases at high velocity; a first grid of fuel distribution pipes; a second grid having inner and outer concentric rings comprised of colinear carburetion and combustion gutters, said inner and outer concentric rings being joined together by radial members comprised of colinear carburetion and combustion gutters; and an additional combustion gutter downstream of said first and second grids and radially 10 15

spaced between said pair of concentric rings of said second grid.
